VENDING MACHINE

Filed May 10, 1929

Gordon B. Macke,
INVENTOR

P. Shockey

WITNESS:

BY *Victor J. Evans*

ATTORNEY

UNITED STATES PATENT OFFICE

GORDON B. MACKE, OF WASHINGTON, DISTRICT OF COLUMBIA

VENDING MACHINE

Application filed May 10, 1929. Serial No. 362,070.

This invention relates to improvements in vending machines, and the present application is a companion case to an application filed by me of even date herewith.

Like the invention disclosed in the application referred to, the present invention has for an object the provision of means to prevent delivery of an article before the machine completes its operation, so that the mechanism of the machine will be ready for the next operation, instead of being apparently inoperative, due to the fact that the article was delivered and the mechanism stopped prior to the return of the parts to their normal positions.

Another object of the invention is the provision of means of the above character which are simple, positive and durable in construction and operation, and may be used in connection with coin controlled vending machines.

With the above and other objects in view, the invention further includes the following novel features and details of construction, to be hereinafter more fully described, illustrated in the accompanying drawings and pointed out in the appended claims.

In the drawings:—

Figure 1 is a sectional view illustrating the invention with the parts in normal position.

Figure 2 is a like view showing the position of the parts after an article has been ejected from the magazine and before the transfer of the article to the delivery compartment.

Referring to the drawings in detail wherein like characters of reference denote corresponding parts, the reference character 10 indicates the housing of the machine which includes a magazine 11 and a delivery compartment 12, the latter having a delivery opening 13 in its front wall.

The magazine is designed to contain various articles 14 to be vended.

Located between the magazine 11 and the delivery compartment 12 is an article receiving compartment 15. This last mentioned compartment is formed by means of vertically spaced laterally offset upper and

lower platforms 16 and 17, the former being disposed directly beneath the magazine 11 and providing a bottom for an ejector slide 18.

The ejector 18 comprises a substantially rectangular frame which, in its normal position as shown in Figure 1, is located directly beneath the magazine 11, so that one of the articles 14 is normally positioned within the frame. This frame slides upon the platform 16 and has extending therefrom a ledge 19. When the ejector is moved outward as shown in Figure 2, this ledge will be located beneath the magazine 11 and act to hold the remaining articles within the magazine until the ejector is returned to its normal position.

With the parts in the position shown in Figure 1, the rod 20 which extends from the ejector is pulled outward so that the lowermost article 14 will be ejected and will fall upon the lower platform 17. The article will remain upon this platform until the ejector is moved inward to its normal position. During this inward movement, the flange or member 21 which extends downward from the ejector and engages the article upon the platform 17, forces said article from the platform into the delivery compartment 12, from where it may be removed through the opening 13.

From the foregoing description and accompanying drawings it will be seen that articles from the magazine will not reach the delivery compartment until the ejector which is mounted for reciprocation, completes its operation. That is, the article will not be transferred from the article receiving compartment to the delivery compartment until the ejector has completed its return movement and again assumes its normal position.

The invention is susceptible of various changes in its form, proportions and minor details of construction and the right is here-in reserved to make such changes as properly fall within the scope of the appended claims.

Having described the invention what is claimed is:—

1. A vending machine including a housing with a magazine and a delivery compartment thereunder, an upper platform in the housing between the magazine and the delivery compartment to provide an ejector support, a lower platform in the housing and disposed in a plane below and forwardly of the upper platform and providing a discharge passage between one end thereof and one end of the upper platform to permit articles to pass into the delivery compartment, an ejector frame slidably mounted and normally positioned under the magazine to receive an article therefrom and adapted to be moved over the lower platform to deliver an article carried thereby onto the lower platform, means on said frame to move the articles positioned on the lower platform through said passage to the delivery compartment by the ejector frame returning to normal position, and means on said frame to underlie the magazine to retain the articles therein when said frame is moved to deliver an article onto the lower platform.
2. A vending machine including a housing with a magazine and a delivery compartment thereunder, an upper platform in the housing between the magazine and the delivery compartment, a lower platform in the housing and disposed in a plane below and forwardly of the upper platform and providing a discharge passage between one end thereof and one end of the upper platform to permit articles to pass into the delivery compartment, an ejector frame slidably mounted and normally positioned under the magazine to receive an article therefrom and adapted to move over the lower platform to deliver an article carried thereby onto the lower platform, a flange at one end of the frame to engage and move the article positioned on the lower platform through the passage and into the delivery compartment during the movement of the ejector frame to its normal position, and means on said frame to underlie the magazine to retain articles therein when said frame is moved to deliver an article onto the lower platform.
3. A vending machine including a housing with a magazine and a delivery compartment thereunder, an upper platform in the housing between the magazine and the delivery compartment, a lower platform in the housing and disposed in a plane below and forwardly of the upper platform and providing a discharge passage between one end thereof and one end of the upper platform to permit articles to pass into the delivery compartment, an ejector frame slidably mounted and normally positioned under the magazine to receive an article therefrom and adapted to be moved over the lower platform to deliver an article carried thereby onto the lower platform, a flange at one end of the frame to engage and move the article positioned on the lower platform through the passage and into the delivery compartment during the movement of the ejector frame to its normal position, and means on said frame to underlie the magazine to retain articles therein when said frame is moved to deliver an article onto the lower platform.
